[57] CLAIM

The ornamental design for a wood stove door, as shown and described.

DESCRIPTION

FIG. 1 is a front perspective view of a wood stove door, showing my new design;

FIG. 2 is an enlarged front elevation view thereof;

FIG. 3 is an enlarged rear elevation view thereof;

FIG. 4 is an enlarged right side elevation view thereof; FIG. 5 is an enlarged left side elevation view thereof; and

FIG. 6 is an enlarged top plan view thereof, the bottom being substantially a mirror image of that shown.

Fig. 1.

Fig. 6.
